UNITED STATES PATENT OFFICE

153,255

DESIGN FOR A VEHICLE

Daniel Boza, Kenmore, N. Y., assignor to Bell Aircraft Corporation, Town of Wheatfield, N. Y.

Application February 5, 1947, Serial No. 136,693

Term of patent 14 years

(Cl. D14—3)

To all whom it may concern:

Be it known that I, Daniel Boza, a citizen of the United States, residing at Kenmore, in the county of Erie and State of New York, have invented a new, original, and ornamental Design for Vehicle, of which the following is a specification, reference being had to the accompanying drawing, forming part thereof.

Fig. 1 is a side elevational view of a vehicle, showing my design;

Fig. 2 is a top plan view thereof;

Fig. 3 is a front end elevational view thereof;

Fig. 4 is a rear end elevational view thereof; and

Fig. 5 is a bottom plan view thereof.

I claim:

The ornamental design for a vehicle, as shown.

DANIEL BOZA.
